UNITED STATES PATENT OFFICE.

PAUL M. HENGSTENBERG, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH.

1,332,040.

Specification of Letters Patent. Patented Feb. 24, 1920.

Application filed January 10, 1917. Serial No. 141,611.

To all whom it may concern:

Be it known that I, PAUL M. HENGSTENBERG, a subject of the German Emperor, and a resident of Wilkinsburg, in the county of Allegheny and State of Pennsylvania, have invented a new and useful Improvement in Switches, of which the following is a specification.

My invention relates to switches and particularly to thermal-responsive quick-acting switches.

One object of my invention is to provide a device of the above indicated character that shall have means for quickly making and breaking a circuit in response to predetermined conditions of temperature.

Another object of my invention is to provide a device of the above indicated character that shall have its contact members electromagnetically actuated in accordance with predetermined conditions.

A further object of my invention is to provide a device of the above indicated character that shall be simple to construct yet effective and efficient in its operation.

In the carrying out of my invention, I provide stationary contact members, a movable bridging contact member normally biased into engagement therewith and having a magnetizable portion at one side thereof. An electromagnet is adapted to attract the magnetizable portion of the bridging member for the purpose of quickly disengaging the same from the stationary contact members, and a bimetallic thermal-responsive device is provided for controlling the energization of the electromagnet. Thus, when the temperature to which the device is subjected reaches a predetermined value, the contact members may be quickly and positively actuated.

In the accompanying drawings, Figure 1 is a front elevational view of a thermal-responsive switch embodying my invention; Fig. 2 is a side view, partially in elevation and partially in section, of the switch shown in Fig. 1; Fig. 3 is a fragmentary sectional view of a portion of the switch shown in Figs. 1 and 2, and Fig. 4 is a fragmentary elevational view of the switch in its open position.

A cylindrical or tubular member 1 is provided with an insulating flange or member 2, at its upper end, and may be open or closed, at its lower end, as desired. Two

stationary contact members 5 and 6 are mounted on the insulating member 2 to constitute the terminals of an electrical circuit 7. A movable bridging contact member 8 is mounted on one end of a substantially flat 60 spring 9 the other end of which is secured to an insulating member 3 that is disposed in the lower portion of the tubular member 1. The bridging contact member 8 is adapted to be held in engagement with the stationary contact members 5 and 6, under normal conditions. The bridging contact member 8 is provided with a magnetizable portion 10 that is adapted to be loosely surrounded by a bimetallic member 11 which is secured, 70 at its lower end, to the insulating member 3. An electromagnet 12 is secured to a supporting member 4 that is mounted on the insulating flange 2, and one terminal 13 of the winding of the electromagnet is operatively 75 connected to an adjustable contact member 14 which is also mounted on the supporting member 4. The position of the contact member 14 is adapted to be adjusted by a screw member 15. A contact member 16 is 80 mounted at the upper end of the bimetallic member 11 and is adapted to engage the contact member 14, under predetermined conditions. The contact members 14 and 16 constitute separable terminals of a circuit comprising the winding of the electromagnet 85 and a source 17 of electromotive force.

When the member 1 is inserted in a hot water heater, a furnace, an oven or other device, the temperature of which is to be 90 controlled, the bimetallic member 11 is adapted to bend under the unequal expansion of its two unlike portions, and its contact member 16 will engage the stationary contact member 14 when the temperature reaches a 95 predetermined value, as determined by the position of the member 14. This will complete a circuit through the winding of the electromagnet 12 for the purpose of energizing the same. When the electromagnet 100 12 is energized, the magnetizable portion 10 of the movable bridging member 8 will be attracted and the member 8 will be quickly disengaged from the stationary contact members 5 and 6. The stationary contact members 5 and 6 may be adapted to control any suitable device in accordance with the application to which the thermal-responsive switch is applied.

When the temperature to which the device 110

is subjected falls below a predetermined value, the bimetallic member 11 will move to such position that the contact members 14 and 16 become disengaged to thus open the circuit of the electromagnet 12 which, when it becomes deenergized, releases the movable bridging member 8 to permit the spring 9 to quickly close the circuit 7.

I do not limit my invention to the particular structure illustrated, as it may be variously modified without departing from the spirit and scope of the invention as set forth in the appended claims.

I claim as my invention:

1. In a circuit-controlling device, the combination with an elongated casing having a supporting member at one end thereof, of a bimetallic member disposed in the casing, stationary contact members and an electromagnet mounted on the supporting member, a bridging contact member supported by the bimetallic member and relatively movable with respect to the same and having a portion adapted to be attracted by the electromagnet, and means whereby the bimetallic member controls the circuit of the electromagnet.

2. The combination with a receptacle having a supporting member around the open end thereof, of a thermal-responsive device disposed in the receptacle, an electromagnet mounted on the supporting member, a movable contact member supported by the thermal-responsive device and relatively movable with respect thereto, and means whereby the electromagnet is controlled by the thermal-responsive device.

3. The combination with a receptacle having a supporting member around the open end thereof, of a thermal-responsive device disposed in the receptacle, an electromagnet mounted on the supporting member, a movable contact member relatively movably supported by the thermal-responsive device and

having means thereon adapted to be attracted by the electromagnet, and means whereby the thermal-responsive device controls the electromagnet.

4. The combination with a receptacle having an outwardly-extending projection at the upper end thereof, of a bimetallic member secured to the lower end of the receptacle, an electromagnet mounted on the projection, an armature for the electromagnet relatively movably supported by the bimetallic member, and means whereby the bimetallic member controls the operation of the electromagnet.

5. The combination with a receptacle, of a bimetallic member mounted therein, an electromagnet, stationary contact members, a bridging contact member for the stationary contact members relatively movably supported by the bimetallic member, means for normally holding the bimetallic member in such position that the bridging member engages the stationary contact members, and means whereby the electromagnet actuates the bridging contact member when the bimetallic member assumes a predetermined position.

6. The combination with a receptacle, of a bimetallic member mounted therein, an electromagnet, stationary contact members, a bridging contact member for the stationary contact members relatively movably supported by the bimetallic member, a spring for normally holding the bimetallic member in such position that the bridging member engages the contact members, and contact members controlled by the bimetallic member for controlling the circuit of the electromagnet, said bridging member being actuated by the electromagnet to disengage the stationary contact members.

In testimony whereof I have hereunto subscribed my name this 30th day of Dec., 1916.

PAUL M. HENGSTENBERG.
